UNITED STATES PATENT OFFICE.

LOUIS DUSSART, OF KINCAID, ILLINOIS.

LIFTING-JACK.

1,333,583.

Specification of Letters Patent.

Patented Mar. 9, 1920.

Application filed September 16, 1919. Serial No. 324,057.

To all whom it may concern:

Be it known that I, LOUIS DUSSART, a citizen of the United States, residing at Kincaid, in the county of Christian and State 5 of Illinois, have invented certain new and useful Improvements in Lifting-Jacks, of which the following is a specification, reference being had to the accompanying drawings.

10 This invention relates to an improved lifting jack for lifting or raising various objects, preferably automobiles and other vehicles and the like, for the purpose of removing the wheels, or changing the tires, or 15 for making other repairs.

As an object of the invention it is the aim to provide a device of this kind, which is simple, efficient and practical in construction, and may be manufactured for a relatively 20 low cost and sold at a reasonable profit.

Another object of the invention is the provision of a lifting jack including a channeled standard provided with a supporting 25 base, and a lifting lever provided with an adjustable pivotal connection in the channel of the standard, whereby an automobile or other vehicle may be raised to various heights, in combination with means for holding the lifting lever, after they have been 30 moved downwardly, and the vehicle raised.

While the design and construction at present illustrated and set forth is deemed preferable, it is obvious that as a result of a reduction of the invention to a more practical 35 form for commercial purposes, the invention may be susceptible to changes, and the right to these changes is claimed, provided they are comprehended within the scope of 40 what is claimed.

The invention comprises further features and combination of parts, as will be hereinafter set forth, shown in the drawings and claimed.

45 In the drawings:

Figure 1 is a view in perspective of the improved lifting jack constructed in accordance with the invention, showing the lifting lever in position, whereby its prying end may engage under an object to be lifted or jacked up.

Fig. 2 is a perspective view showing the lifting lever lowered, and the object raised.

Fig. 3 is a vertical sectional view on line 3—3 of Fig. 2.

Fig. 4 is a transverse sectional view on line 4—4 of Fig. 2.

Referring more especially to the drawings, 1 designates a base adapted to engage the ground or floor of a garage, in order that the standard 2 which rises upwardly from the base may be held firm and in a perpendicular position. The standard 2, which rises upwardly from the base 1 is channeled vertically, to receive the lifting lever 3. 60 This channel 4 is of a width, so that the lifting lever may fit neatly between the sides of the standard, sufficiently to brace the lifting lever when it is lowered and its object raised. Furthermore the channel acts to guide the 70 lifting lever, when in the act of being lowered. The opposite sides of the standard are provided with a plurality of registering apertures 5. The lifting lever near the lower portion thereof is provided with a transverse opening or aperture 6.

The opposite sides of the standard at its upper end is provided with registering apertures 7. The lifting lever near its upper portion is provided with a plurality of 80 spaced apertures 8. A pivot pin or stud 9 passes through the apertures 7 and also through any one of the apertures 8, for holding the lifting lever in different adjusted positions, whereby the prying end of the 85 lever may be used for lifting objects to various heights. The upper end of the lifting lever terminates in an enlarged head 10. This head has laterally extending portions 11, which overlie the upper edges of the 90 sides of the channeled standard. The lower ends of the overlying laterally extending parts 11 have beveled portions 12. The face of the standard opposite the open portion of the channel near the upper end of the standard is cut away as shown. In other words, the upper end of the standard is bifurcated as indicated at 13, whereby the lifting lever

may be moved to a position, either in a horizontal plane, or in inclined positions above 100 or below a horizontal plane. For example, when the lifting lever is positioned so that its prying end or head 10 may engage under an object to be lifted, the lower end of the lifting lever may be raised above a horizontal plane, so that the prying end or head 10

of the lifting lever may attain a better purchase on the object to be lifted. The upper ends of the sides of the channeled standard from a point adjacent the crotch of the bifurcation 13, to the upper end edges of the sides of the channeled standard are curved, as shown at 14, so as to permit freedom of movement of the laterally extending overhanging parts 11 of the prying head 10 of the lifting lever, so as to permit the lifting lever to move to a position above a horizontal plane. The upper end edge of the prying head 10 of the lifting lever is bifurcated as shown at 15. The crotch of this bifurcation is wide enough to engage under various objects to be lifted, such as an axle of an automobile or other vehicle or any other part. Furthermore, this crotch is curved or rounded in cross-section, so as to permit the crotch of the bifurcation to easily slide relative to the object to be lifted, as the longer or lower arm of the lifting lever is being moved downwardly. The end flanges 16 of the bifurcation 15 constitute means to prevent the crotch of the bifurcation from slipping laterally out of engagement with an object to be lifted. The inner faces of these flanges 16 are beveled and rounded correspondingly to the rounded or curved face of the crotch 15, so that the flanges, should they contact with an object to be lifted, will easily slide. When the lifting lever has been moved so that the prying head thereof lifts an object, and also so that the lifting lever is allowed to enter the channel of the standard, a pin or key is inserted through any one of the plurality of registering apertures 5 of the opposite sides of the channeled standard, and through the apertures 6 of the lever, so as to hold the lever in its lowered position. In other words, by means of this key or pin, the lifting lever is held in a vertical position in parallelism with the adjacent walls of the channel of the standard, with the prying head 10 under the object to be lifted. When the lever is in such a position, the crotch of the bifurcation of the prying head of the lever is in engagement with the object. The outer face of the lifting lever has secured thereto as at 18 a handle 19, by which the lifting lever may be removed or swung out of the channel of the standard, so that the lever may be raised toward or above a horizontal plane.

55 The invention having been set forth, what is claimed as new and useful is:

1. In a lifting jack, the combination with a standard provided with a base, and having one face channeled vertically for its full length, the upper end of the channel being open, the upper end of the standard being bifurcated, of a lifting lever adjustable and pivotally mounted between the side of the upper end of the standard and engaging said bifurcation, said lifting lever comprising

ing a prying head having a rounded bifurcation to engage an object to be lifted, and also including an elongated leverage arm, adapted to enter the lower part of the channel, when the lifting lever is in a perpendicular position with the channel, said bifurcation of the upper end of the standard constituting means to permit the lifting lever to move freely, and allow the leverage arm to assume a position near or above a horizontal plane, when the lifting lever is moved pivotally, the lower portions of the sides of the standard having a plurality of apertures, the lower portion of the leverage arm having an aperture, and a pin adapted to extend through any one of the apertures of the lower portions of the sides of the standard, and through the aperture of the leverage arm, to correspond with the adjustment of the pivot of the lifting lever, so as to hold the lifting lever within the channel and in a perpendicular position.

2. In a lifting jack, the combination with a base, and a standard constructed integrally and as one piece with the base and rising perpendicularly from the base, said standard being U-shaped in cross section, the opposite sides of the standard near its upper end having registering apertures, the lower portions of the sides of the standard each having a plurality of apertures registering with those of the opposite side, of a lifting lever engaging between the sides of the standard, the upper portion of the lever having a plurality of apertures, a thumb screw to engage through the apertures of the upper ends of the sides of the standard and through the upper apertures of the lever, to pivotally mount the lever on the standard, the upper end of the cross connecting wall between the sides of the standard being cut away, whereby the sides of the standard may act as extensions to receive the upper thumb screw and to support the lever, said cut away part of the cross connecting wall causing a bifurcation to be formed whereby the lever may move to a horizontal position, said lever having a prying head provided with a rounded edge to cam under an object to be lifted and provided with end flanges to coöperate with the object to prevent lateral displacement of the head, the lower end of the lever having an opening, and means passing through any two of the apertures of the lower end of the standard and through the opening of the lever to hold it between the sides of the standard.

3. In a lifting jack, the combination with a base, of a standard rising integrally therewith and disposed perpendicularly, said standard being U-shaped in cross section, the upper end of the standard having a bifurcation, of a lever pivoted adjustably in said bifurcation and having a lifting

head at one end, said lifting head having an upper rounded edge to cam against an object to be lifted, the ends of the rounded edge terminating in flanges to coöperate with the object to be lifted to prevent lateral movement thereof, and adjustable means passing through the lower part of the sides

of the standard and through the lower end of the lever correspondingly to the adjustability of the lever, to hold the lever between 10 the sides of the standard.

In testimony whereof I hereunto affix my signature.

LOUIS DUSSART.
